UNITED STATES PATENT OFFICE

ARVID ANDERSSON, OF BOSTON, MASSACHUSETTS, ASSIGNOR TO PEERLESS MACHINERY COMPANY, OF BOSTON, MASSACHUSETTS, A CORPORATION OF MASSACHUSETTS

CEMENTING MACHINE

Application filed January 2, 1929. Serial No. 329,728.

This invention relates to a machine for applying cement to leather and other materials and although designed with special reference to the use of latex cement for the cementing of soles to shoe uppers in the shoe manufacturing industry, yet it is capable of various other uses.

Latex cement is made up of rubber globules carried by water in the form of an emulsion and is highly fluid which makes it difficult to apply except with a brush which operation is slow and expensive.

The main object of the invention is the provision of a simple and an efficient machine adapted for rapidly applying latex cement to shoe parts and other kinds of work.

Another object of the invention is the provision of means in a cementing machine for applying by pressure a highly fluid cement to the roughened surfaces to be cemented in order to cause the cement to permeate the body of the work and thereby to anchor itself therein.

A further object is the provision of means for controlling automatically the flowage of a highly fluid cement from a source of supply to the applying means to secure an adequate and even distribution of the cement.

An additional object is the provision of means for automatically shutting off the supply of cement without stopping the machine whenever the work is removed from the machine.

Other objects of the invention will be more specifically pointed out and described hereinafter.

In its preferred embodiment, my invention contemplates a machine comprising a rotary cement applying member cooperating with a rotatable work support for applying the cement and pressing it into the work to cause it to permeate the fibrous body thereof. The cement is fed by gravity from a suitable receptacle arranged above the rotary applying member and controlled by a valve normally closed but opened intermittently to permit the cement to flow in successive drops or small quantities upon said member. The machine is designed to operate continuously to avoid frequent starting and stopping but

when the work support is depressed to permit work to be inserted in or removed from the machine the means for opening the valve intermittently is thrown out of operation to stop the feeding of cement and the parts may be locked in such inoperative position if desired.

Referring to the accompanying drawings illustrating the preferred form of the invention, Figure 1 is a side elevation, partly in section, of a machine constructed and adapted to be operated in accordance with my invention; the operative parts being shown in operative position; Fig. 2 is a partial side elevation of the same with the operative parts of the machine in inoperative position; Fig. 3 is a transverse sectional view on line 3-3 in Fig. 2 looking from left to right; Fig. 4 is an end elevation of the cement applying member; Fig. 5 is a side elevation of the same member; Fig. 6 is a plan view of the treadle mechanism in locked position and Fig. 7 is a side elevation of the same mechanism in unlocked position.

Referring to the illustrated embodiment of the invention, the frame of the machine is of the skeleton type comprising a base 10 of rectangular form having four corner webs 12 springing upwardly from the four corners of the base and converging to be united by a top cross web 14. The webs 12 are T-shaped in cross section to impart the necessary strength and rigidity to the frame but it may be made, however, in any suitable manner. The two rear webs 12 are united at their upper ends to form an extension 16 having bored expanded portions 18 and 20 to serve as bearings for shafts and the two front webs 12 are similarly united at their upper ends to form an extension 22, bored in alignment with the bores in the extension 16 for two shafts.

Mounted in the bores in the two extensions 16 and 22 are two shafts 23 and 24, the upper one being a main shaft and the lower one a work support rotating shaft. Fastened to one end of the main shaft 23 is a pulley wheel 25 adapted to receive a belt for operating the machine from any suitable source of power.

For applying the cement to the work, a

roll 27 is fixed on the other reduced end of the main shaft by a screw 28 threaded into the end thereof, any relative movement between the roll and shaft being prevented by a pin 29 in the shaft engaging a slot 30 in the hub 31 of the roll. The periphery of the roll is preferably knurled and the roll may be made in one piece or built up as shown of a number of disks.

For supplying cement to the applying roll 27, a cylindrical reservoir or receptacle 34 having a cone-shaped bottom 35 is mounted above the said roll by means of a downwardly extending integral plate 36 which is fastened to an upwardly extending plate portion 37 of the frame of the machine by a screw 38 and butterfly nut 39. The bottom edge of the receptacle plate 36 rests upon a shoulder 40 formed in the frame which serves as an abutment to prevent pivotal movement of the receptacle on the screw 38. A cover 41 having oppositely disposed pairs of locking projections 42 is held on the reservoir by a pair of clamps each comprising a screw pin 43 pivotally mounted in ears 44 and a butterfly nut 46 engaging said locking projections. To permit filling the receptacle the cover may be provided with a flanged opening 48 closed by a cap 49.

For controlling the flow of cement from the receptacle a cone valve is threaded into the apex of the cone-shaped bottom of the receptacle and is provided with a bottom opening 51 through which the cement may flow out upon the roll 27. Within the receptacle is mounted a valve spindle 53 having its lower end cone shaped to fit the lower end of the valve chamber in the valve 50 and at its top, the valve spindle is threaded into the collar portion of a yoke 55 pivotally mounted on a screw 56 carried by a lever 57 which in turn is pivotally mounted at one end on a pin 58 carried by ears 59 either attached to or forming an integral part of the cover 41. The cover may be provided with a central opening through which the valve spindle passes.

For operating the valve spindle to open the valve intermittently a sleeved cam 60 is keyed to the main shaft 23 and is provided with a series of peripheral projections 61 spaced apart for raising a rod 62 slidably mounted in brackets 63 and 64 on the cement receptacle. The upper end of the rod 62 engages a screw pin 65 threaded through the end of the valve spindle lever 57 and when the rod is raised by a projection on the cam the valve spindle is raised by the arm 57 to open the valve to permit a small amount of cement to drop upon the roll 27. The extent of the opening is regulated by adjusting the screw pin 65 in which position it is held by a set nut 66. A spring 67 fastened at one end to a hook 68 in the end of the valve spindle lever and at the other end to a hook 69 in

the bracket 63 holds the lever down and the valve closed. For adjusting the throw of the rod 62 a collar 70 is fastened thereto by a screw 71 and by engagement with the bracket 64 holds the rod in suspended position subject to the raising action of the projections on the cam. These adjustments make it possible to control the flow of the cement from the receptacle to a very fine degree and to conform to cements of various degrees of fluidity.

For supporting the work an elongated stud 73 carrying a disk work support 74 is slidably mounted in the bored ends of a yoke 75 secured to the frame of the machine by bolts 76. The stud is inclined outwardly so that the bevelled portion of the upper face of the disk is parallel to the surface of the cement roll and supports and feeds the work in co-operation with said roll. The work support is adapted to be rotated by the shaft 24 through the medium of a bevelled gear 77 mounted on the stud 73 between the bifurcations of the yoke 75 and held in position by a collar 78. The hub of the gear extends upwardly into the upper bifurcation of the yoke and the gear is keyed to the stud 73 by means of a longitudinal slot 79 in the inner face of the hub of the gear in which projects a longitudinal key 80 formed on the stud. The gear meshes with a bevelled gear spindle 81 fastened to the end of the shaft 24 by a screw 82 and the shaft 24 is rotated from the main shaft by gears 83 and 84 secured to their respective shafts by hub screws 85 and 86. In order that the operative surface of the work support 74 may travel at the same speed as the cement applying member, the two gears 83 and 84 are suitably proportioned to bring about this result.

For holding the work support in operative position and close to the cement applying roll, a lever 88 is pivotally mounted on a pin 89 set in the frame of the machine, one end of the lever being bored to receive a hook 90 to which is attached a helical spring 91 having its lower end connected to a hook 92 set in the base of the frame. Upon the threaded shank of the hook 90 is a butterfly nut 93 for adjusting the tension of the spring. The other end of the lever 88 is split to form a yoke which partially encloses a flanged collar 95 threaded on the lower threaded end of the work support stud 73, the yoked end of the said lever being held in position by an end washer 96. The tension of the spring 91 holds the stud and work support in an uppermost position with the work support close to the cement applying member. By turning the collar 95 on the end of the stud the work supporting disk may be adjusted in relation to the cement roll which determines the pressure to which the work is subjected between the cement roll and the disk.

For depressing the forward end of the lever 88 to pull down the work support for the insertion of work in or removal from the machine, the yoked end of the arm 88 is connected by a link 98 to a treadle rod 99 which in turn is connected to a treadle 100, pivotally mounted on a pin 101 in ears 102 on a plate 103 which may be fastened to the floor. One end of said treadle carries a foot piece 104 and the other end is bored and threaded to receive a screw 105 for locking the treadle in a depressed position when desired. The plate 103 is L-shaped and has on its rear end a projecting block 106 fastened thereto by a screw 107. The treadle is loosely mounted in the ears 102 so that it may be turned on its pivot laterally to a slight degree and to lock it, the operator after depressing the treadle gives the foot a slight impulse to the right (see Figs. 6 and 7) thereby bringing the end of the pin 105 to rest on the upper face of the block 106. To release the treadle from its locked position the foot piece end is moved slightly to the left carrying the screw 25 105 away from the block 106.

To eliminate the friction between the flange of the collar 95 and the yoked end of the lever 88 due to the upward pressure of that end on the flange caused by the spring 91, 30 there is mounted on the collar between the flange and the end of the lever a ball bearing 108 comprising two rings with a series of interposed balls. The ring in engagement with the end of the lever remains stationary 35 but the other ring rotates with the collar.

Whenever the work support is depressed it is desirable that the feeding of cement to the applying member be stopped and means is therefore provided for throwing the valve 40 operating mechanism out of operation on the depression of the treadle. Any suitable means may be employed for this purpose and one such means is shown comprising a bell crank lever 112 pivotally mounted on a screw 45 113 mounted in the cross web 14. At its lower end the bell crank lever is connected to the lever 88 by a turn buckle link 114. The end of the upper arm of the bell crank lever is in the form of a yoke partially enclosing 50 the sleeved portion of the cam 60 between two annular flanges 115. When the treadle is depressed that end of the lever 88 connected to the bell crank lever is raised which throws the upper arm of the latter lever to the right 55 thereby moving the cam 60 in the same direction on the main shaft and out of engagement with the valve operating rod 62. The continued operation of the machine thereafter produces no effect upon the valve of the cement receptacle and it remains closed. When 60 the treadle is raised, the operation of the bell crank lever throws the cam back into operative position and the intermittent opening of the valve is resumed.

In the operation of the machine, the valve

operating mechanism is first adjusted to suit the kind of cement used and this adjustment can be varied to a considerable degree by adjusting the screw 65 and the collar 70. When a cement of the character of latex is being used, the fluidity of which is nearly equal to that of water, the throw of the valve spindle is very slight and the cement will be fed to the roll rather in the form of drops than as a stream. With heavier cements, however, the valve spindle should have a wider range of movement dependent upon the consistency of the cement. The machine can, however, be adjusted to a variety of cements. The amount of pressure to which the work is subjected between the cementing roll and the work support is also subject to adjustment to suit varying conditions of work, cement and results desired.

After adjustments are made and the machine started, the operator depresses the treadle to lower the work support and places the work thereon and against an edge gage 120 adjustably secured in the frame by screw 121 and then releases the treadle. The work is fed through by the cooperative action of the cementing roll and the work disk and the cement is pressed into the body of the work.

Whenever the use of the machine is discontinued for a short interval the operator depresses the treadle and gives it a slight sidewise movement to lock it whereupon the feeding of cement to the applying roll is discontinued although the machine still operates. The continued operation of the machine avoids the delay incidental to starting and stopping it when work is inserted in or removed from the machine and speeds up the application of cement to the work. By stopping the feeding of cement to the rotary member when there is no work in the machine any undue accumulation of cement upon the rotary member is avoided.

The use of my machine is especially of advantage in applying cement of the character of latex cement to soles which have been roughened to be cemented to shoe uppers and especially to soles which have been roughened by the cutting of a plurality of parallel channels. In applying cement to soles so prepared, the rotary member first floods the channels with the latex cement and then presses the cement into the body of the sole flattening out the partitions between the channels by pressure with the result that when the cement has dried it is anchored in the body of the sole and will permanently bond the sole to the shoe upper.

Although my machine is especially adapted for applying latex cement, it is to be understood that other kinds of quick flowing cements may be used in the machine to advantage and by adjusting the valve, the ma-

chine may be adapted to cements of various degrees of fluidity.

It is to be understood that the form of the invention hereinbefore shown and described is for the purpose of illustration only and that my invention may be embodied in various other forms of construction within the purview of the following claims.

What I claim is:

10. 1. A cementing machine having, in combination, a rotary cement applying member, a rotary work-support for feeding the work, a cement reservoir for supplying cement by gravity to said applying member, a valve controlling the flow of cement from said reservoir, said valve being normally closed, a shaft and means including a rotary cam for intermittently opening said valve during each revolution of said shaft to permit cement to flow from said reservoir onto said cement applying member.

20. 2. A cementing machine having, in combination, a rotary cement applying member, a rotary disk work-support for feeding the work, a cement reservoir for supplying cement by gravity to said applying member, a normally closed valve for controlling the flow of cement from said reservoir, a main shaft and automatic cam operated means for intermittently opening said valve on each revolution of said main shaft to permit cement to flow intermittently from said reservoir onto said cement applying member.

30. 3. A cementing machine having, in combination, a rotary cement applying member, a reservoir for holding cement, a normally closed valve in said reservoir, automatic means for opening said valve intermittently to permit the flow of cement onto said applying member during the operation of the machine and treadle operated means for throwing said automatic means out of operation at the will of the operator.

40. 4. A cementing machine having, in combination, cement applying means, a reservoir for holding a supply of cement, a normally closed valve in said reservoir and adjustable automatic means for opening said valve intermittently to permit cement to flow onto said cement applying means and treadle operated means for throwing said automatic opening means out of operation at the will of the operator.

50. 5. A cementing machine having, in combination, a cement applying member, a reservoir located thereabove for holding a supply of cement and having an opening for the flow of cement from said reservoir onto said applying member, a valve for normally closing said opening and automatic means for opening said valve intermittently so long as the machine operates and treadle operated means for throwing said automatic means out of operation at the will of the operator with-

out interfering with the operation of the machine.

6. A cementing machine having, in combination, a cement applying member, a reservoir for holding a supply of cement and located to feed cement by gravity to said cement applying member, a valve for controlling the flow of cement from said reservoir, said valve being normally closed, cam operated means for intermittently opening said valve, a depressible work support, a treadle for depressing said work support and means for throwing said cam operated means out of operation whenever said work support is depressed.

7. A cementing machine having, in combination, a cement applying member, a reservoir for holding a supply of cement and located to feed cement by gravity to said cement applying member, a valve for controlling the flow of cement from said reservoir, said valve being normally closed, cam operated means for intermittently opening said valve, a depressible work support, a treadle operated means for depressing said work support, means for throwing said cam operated means out of operation whenever said work support is depressed and means for locking said treadle when depressed in order to hold said work support in a lowermost position and said cam operated means out of operation.

8. A cementing machine having, in combination, a reservoir for holding a supply of cement and having an outlet opening in its bottom, a valve controlling said opening and being normally closed, automatic means including a shaft and a cam mounted thereon for opening said valve intermittently on each revolution of said shaft and means located beneath said reservoir for pressing said cement into the body portion of the work to be coated.

9. A cementing machine having, in combination, a cement receptacle, a valve normally closed for controlling the flow of cement from the said receptacle, automatic means including a shaft and a cam mounted thereon for opening said valve intermittently on each revolution of said shaft, cement applying means beneath said receptacle and a spring pressed work support for pressing the work against said cement applying means to force the cement into the body of the work.

10. A cementing machine having, in combination, a cement receptacle, a valve normally closed for controlling the flow of cement from the said receptacle, automatic means including a shaft and a cam mounted thereon for opening said valve intermittently on each revolution of said shaft, cement applying means beneath said receptacle, a spring pressed work support for pressing the work against said cement applying means to force the cement into the body of the work and means

for rotating said cement applying means and said work support to feed the work.

11. A cementing machine having, in combination, a cement applying member, a cement reservoir, a normally closed valve for controlling the flow of cement from said reservoir, cam operated means for intermittently opening said valve and treadle operated means for throwing said cam operated means 10 out of operation without stopping the machine.

12. A cementing machine having, in combination, a cement applying member, a cement reservoir, a normally closed valve for controlling the flow of cement from said reservoir, a main shaft and means operated by said main shaft for opening said valve for a series of intermittent periods during each revolution of said main shaft.

13. A cementing machine having, in combination, a cement applying member, a rotary disk work support for feeding the work, a cement reservoir, a normally closed valve for controlling the flow of cement from said reservoir, a shaft, a cam mounted on said shaft and provided with a plurality of peripheral cam surfaces and means intermediate said valve and said cam adapted when engaged by a cam surface to open said valve.

14. A cementing machine having, in combination, a cement applying member, a cement reservoir, a normally closed valve for controlling the flow of cement from said reservoir, a main shaft, means, including a cam provided with a plurality of peripheral cam surfaces, operated by said main shaft for opening said valve for a series of intermittent periods during each revolution of said main shaft and means within the control of 40 the operator for throwing said cam out of operation without stopping the machine.

15. A cementing machine having, in combination, a cement applying member, a cement reservoir, a normally closed valve for controlling the flow of cement from said reservoir, a main shaft, means, including a cam slidably mounted on said main shaft, operated by said main shaft for opening said valve for a series of intermittent periods 50 during each revolution of said main shaft and means for moving said cam longitudinally of said shaft and out of operative position at the will of the operator and without interfering with the rotation of said shaft.

16. A cementing machine having, in combination, a cement applying member, a work support, a cement reservoir, a normally closed valve for controlling the flow of cement from said reservoir, a shaft, a cam mounted on said shaft and provided with a plurality of peripheral cam surfaces, means intermediate said valve and said cam whereby the rotation of said shaft opens said valve for a series 60 of intermittent periods equal in number to

the number of cam surfaces on said cam during each revolution of said shaft.

17. A cementing machine having, in combination, a cement applying member, a cement reservoir, a normally closed valve for controlling the flow of cement from said reservoir, a main shaft, means, including a cam slidably mounted on said main shaft, operated by said main shaft for opening said valve for a series of intermittent periods 70 during each revolution of said main shaft and means for sliding said cam out of operative position to hold said valve closed during the revolution of said shaft.

18. In a cementing machine, the combination of a reservoir for cement having a discharge opening, a lever pivotally mounted at one end on said reservoir, a valve spindle pivotally connected at its upper end to said lever for closing said opening in said reservoir, a main shaft, a cam mounted on said main shaft provided with a plurality of peripheral cam surfaces, a vertical rod having its lower end in engagement with said cam and its upper end in engagement 80 with said lever and means for rotating said main shaft to open said valve at intermittent periods during each revolution thereof.

In witness whereof, I have hereunto set my hand this twenty-ninth day of December, 1928.

ARVID ANDERSSON.
